CLAIM

The ornamental design for a ram-air intake, as shown and described.

DESCRIPTION

FIG. 1 is a perspective view of a ram-air intake showing my new design;

FIG. 2 is a first side view thereof;

FIG. 3 is a second side view thereof;

FIG. 4 is a top view thereof;

FIG. 5 is a bottom view thereof;

FIG. 6 is a back view thereof;

FIG. 7 is a front view thereof; and,

FIG. 8 is a front view showing the ram-air intake in use.
The broken lines illustrate portions of the ram-air intake that do not form a part of the claimed design. The embodiment shown is for the left side of a vehicle. The invention includes mirror images of the ram-air intake shown in the Figures.
